Jesse R. Langley
ATTORNEY.

UNITED STATES PATENT OFFICE

J RAYMOND JONES, OF SPRING HOUSE, PENNSYLVANIA, ASSIGNOR TO ALAN WOOD STEEL COMPANY, A CORPORATION OF PENNSYLVANIA

RUNNING BOARD FOR RAILWAY CARS

Application filed July 23, 1930. Serial No. 469,963.

My invention relates to running boards for railway cars and particularly to running boards for railway tank cars.

Running boards for various types of railway cars have, in general, been constructed of wood, the boards extending lengthwise of the running board and, in certain cases, two or more boards have been required to constitute the width of the running board.

10 Wooden running boards have the disadvantage that they are exposed to the weather and that they decay within a comparatively short time. Such decay is not always apparent before the running boards are in unsafe condition. It will be appreciated that a loose board with a projecting end or a decayed board that is insufficient to bear the weight of a person constitutes a material source of danger.

20 Furthermore, wooden running boards become dangerous when they are covered with a slight film of ice or snow by reason of the tendency of persons to slip when walking upon them.

25 In running boards constructed in accordance with my invention, I provide metal plates, the upper surface of which has extending therefrom a comparatively large number of projections which, for example, may be of modified diamond form. These projections are for the purpose of insuring safe footing when walking over the running board and are effective even when the upper surface of the plate is covered with ice or snow.

35 The sides of the metal plates are provided with flanged edges which operate both as reinforcing devices and as guard devices for preventing missteps and for shielding the edges of the plates.

40 The details of my invention will be described in connection with the accompanying drawing, in which

Figure 1 is a plan view of a railway-tank car with the tank removed;

45 Fig. 2 is a vertical sectional view of the structure of Fig. 1, taken on line 2—2 thereof with the tank in position;

50 Fig. 3 is a fragmentary view, in side elevation, of the tank and certain of its associated parts;

Fig. 4 is a perspective view of a corner portion of the running board; and

Fig. 5 is an enlarged elevational view showing the details of the supporting means for the running board and taken on line 5—5 of Fig. 1.

A railway-tank car 1 comprises the usual framework 2, including transverse beams 3, which may be of metal or other suitable material. The frame is supported in the usual manner by trucks 4.

The tank 5, which is shown in Figs. 2 and 3, is supported by the frame 2 and is secured thereto in any suitable manner. The tank 5 is provided with a usual dome 6.

65 A running board 10 is supported at the outer ends of the transverse beams 3 and extends entirely around the periphery of the car. The rectangle thus formed constitutes a passageway on all sides of the tank 5. The running board 10 comprises a continuous series of flat metal plates 11, the upper surfaces of which are provided with projections 12 of suitable shape so as to provide security from slipping for persons walking thereon. The 70 projections 12 may be of any desired number or form, such as oblong or of modified diamond form, and extending longitudinally of the plates.

75 As best shown in Figs. 4 and 5, the inner edges of the several plates 11 are provided with an upturned flange 13 and the outer edges of the plates are similarly provided with a downwardly turned flange 14. The purpose of the inner flange is to operate both as a reinforcing means and also as a guard flange to prevent overstepping the inner edge of the running board.

80 The purpose of the outer flange 14 is to provide reinforcing means and, in addition, to avoid a relatively sharp thin edge such as would be present if no flange were provided. Such sharp edge might cause accidents by reason of its engaging the clothing or shoes of persons climbing upon the running board.

85 The manner in which the plates are joined at the corners of the running board is shown in Fig. 4. It will be noted that one of the side plates extends to the end of the running 90

95

100

board and that the other or end plate which is at right angles thereto ends at the inner edge of the first plate, except that its outer flange 14 extends under the end of the side plate to constitute, in effect, an end flange therefor.

In the same view, it will be noted that the adjacent corners of the inner flanges 13 are rounded in order to avoid sharp projections at this point. This arrangement is also in the interest of safety.

It is often desirable to replace wooden running boards with the improved running boards of my invention and, in such case, the construction shown in Fig. 5 may be employed. The metal plates 11 are secured to the beams 3 by means of spacers 16 in order to compensate for the greater thickness of the wooden running board and its support.

On the sides of the tank 5 and adjacent to the dome 6 are two platforms 17, comprising metal plates 18 of the same general character as those of the running board 10. The plates 18 are supported on brackets 19 and are provided with loops 20 to be grasped by a person climbing to one of the platforms 17. A portion of the outer flange of each of the plates 18 is cut away in order to render the loop 20 readily accessible.

The running board of my invention provides an extremely durable structure and an arrangement that contributes to the safety of the users. The rough upper surface of the metal plates provides an insurance against slipping in case of inclement weather and the arrangement is such as to contribute materially to the neat appearance of the car.

The foregoing and other advantages will be appreciated by those skilled in the art of railway car construction and operation.

I claim as my invention:

1. A running board for railway tank cars comprising a continuous series of horizontal metal plates with vertical flanged edges, certain of said plates extending at right angles to each other and an outer flanged edge of one of said plates overlapping an end of an adjacent plate.

2. A railway tank car having a rectangular frame, a tank supported on said frame, a substantially continuous running board on said frame and surrounding said tank and comprising metal plates with upper surfaces provided with projections, said running board having a substantially continuous inner upturned and outer downturned flanges throughout its length and certain of said plates having portions overlapping other plates at the corners of said running board.

3. A railway tank car having a rectangular frame, a tank supported on said frame, a substantially continuous running board on said frame and surrounding said tank and comprising metal plates with upper surfaces provided with projections, and platforms of

similar material secured to upper portions of said tank and provided with flanged edges having portions cut away and loops adjacent such cut-away portions.

4. A running board for railway cars comprising a series of metal plates supported upon framework, spacing members between said framework and said plates and an outer downwardly turned flange for said plates the width of which is substantially equal to the height of said spacing members.

In testimony whereof, I have hereunto subscribed my name this 22nd day of July 1930.

J RAYMOND JONES.
